UNITED STATES PATENT OFFICE.

ARTHUR G. HAWKES, OF CHICAGO, ILLINOIS, ASSIGNOR TO THE PULLMAN COMPANY,
A CORPORATION OF ILLINOIS.

COUPLER-PIN LIFT.

Application filed May 31, 1923. Serial No. 642,693.

This invention relates to car coupling devices and more particularly to the uncoupling mechanism or devices for lifting the coupler or locking pins of couplers employed for connecting the cars of railway trains and the like.

One of the objects of the invention is the provision of new and improved uncoupling rigging or mechanism that is constructed of a minimum number of parts but at the same time will permit the necessary longitudinal, lateral and vertical movements of the coupler, incident to the travel of the car.

Another object of the invention is the provision of a simple, strong and durable improved device of this character which may be easily manipulated and one that is efficient and reliable in operation.

Other and further objects and advantages of the invention will appear from the following description, taken in connection with the accompanying drawings, in which

Fig. 1 is a plan view of a portion of a railway car showing the invention in position thereon, parts in section and parts broken away;

Fig. 2 is a front elevation of Fig. 1 with the coupler removed and with parts broken away;

Fig. 3 is a side elevation of Fig. 1; and

Figs. 4 and 5 are details of a modified form of the device.

On the drawings, the reference character 10 designates a car, and 11 a coupler therefor including a coupler pin 12 for locking the knuckle 13, all of which are of the usual or well known construction.

Referring to Figs. 1, 2 and 3, a horizontally arranged rock shaft 14 is pivotally or rotatably mounted in loops or brackets 15 and 16 suitably secured along the end of the car. The outer end of the shaft 13 is provided with the usual laterally extending arm or handle 17 by means of which it is turned or rotated. The shaft 14 is also provided with an apertured flattened portion 18 which is normally in horizontal position. The parts are so arranged that the flattened portion is in a substantially horizontal plane while the arm or handle extends downwardly.

Suitable mechanism connecting the shaft 14 and the pin 12 is provided for releasing

the knuckle 13. This mechanism is so constructed that it will permit longitudinal, vertical and lateral movements of the coupler relatively to the car. One form of the device selected to illustrate the invention will now be described.

Pivottally attached to the flattened portion of the shaft 13, as by means of the pivot 19, is an arm 21 the free end of which is adapted to engage the coupler pin 12 for lifting the same to release the knuckle 13. As shown, the arm 21 is provided with a recess for engaging the flattened portion of the rock shaft. In other words, the arm is bifurcated at its inner end, forming the plates 23 and 24 which engage each side of the flattened portion and are provided with suitable apertures through which the pivot pin 19 may extend. The pivot pin merely holds the parts in assembled relation. This interlocking connection between the arm and the shaft causes the arm to move when the shaft is rotated. From the pivot 19 the arm extends downwardly and outwardly at an angle to the shaft 14 and has its free end bent to extend substantially parallel with said shaft for slidably engaging the eye of the pin 12, the free end of the arm being reduced for this purpose, as shown at 25.

The end 25 of the arm 21 makes a loose fit in the eye of the pin 12 in order to permit sliding, turning and a limited pivotal movement of the end 25 in the eye 12. By this arrangement, vertical movement of the coupler is provided for by the turning of the rock shaft 14; lateral movement by the sliding of the end or reduced portion 25 through the eye 12; and movement longitudinally of the car is provided for by the pivotal movement of the arm 21 about the pivot 19 and a slight pivotal movement in the eye 12.

The modified form of the device shown in Figs. 4 and 5 differs from that just described only in the manner in which the arm is pivotally connected to the rock shaft. In this form, an interlocking connection is provided for this purpose whereby the use of a pivot pin is unnecessary. As shown, the rock shaft 14^a is provided with a flattened portion 18^a arranged as in the other form except that the front and rear edges may be

struck on the arc of a circle from the center of the flattened portion, as shown at 28. The arm 21^a is provided with an elongated recess or slot 26 having curved ends to correspond 5 with the curved edges 28. The shorter dimension of the recess or slot is slightly less than the diameter of the rock shaft. The recess or slot has a lateral extension 27 in one wall arranged at right angles to the 10 arm whereby the arm may be slipped in position on the shaft by turning the same at right angles thereto so that the round portion 29 on the corresponding side of the shaft 14^a will register with the depression. 15 After the arm engages the flattened portion, it is turned to thereby prevent its removal. While the shaft and arm have been described in both forms of the device as being provided with a flattened portion and a recess, 20 respectively, it is understood that the parts may be interchanged, if desired. The operation of this form of the device is substantially the same as that just described.

It will be understood that various changes 25 in the form, construction, composition and arrangement of the several parts may be resorted to without departing from the spirit and scope of my invention; hence I do not wish to limit myself strictly to the structure 30 herein set forth, but

What I claim is:—

1. In a device of the class described, a rock shaft, means for operating said shaft, an arm having a slot in one end for engaging 35 said shaft, and a pin extending through said shaft and the slotted end of said arm for pivotally connecting said arm to said shaft, said arm extending at an angle to said shaft and provided with an extension for operating a coupling pin.

2. In a device of the class described, a rock shaft having a flattened portion between its ends, a handle for operating said shaft, an arm, means for pivoting said arm 45 to said flattened portion whereby the latter may function as a lever to raise said pin, and means on said arm for slidably engaging the eye of a coupling pin.

3. In combination, a car, coupler mechanism for said car including a coupler pin, 50 a comparatively straight rock shaft member, a pair of bearings for rotatably mounting said rock shaft member on said car, an arm member pivotally connected to said rock shaft member between said bearings, one of said members being provided with 55 a distorted portion and the other with means for engaging said distorted portion, and means for holding said members in pivotal engagement.

4. In combination, a car, coupler mechanism for said car including a coupler pin, a rock shaft comprising an approximately 60 straight body portion, and a handle portion extending at an angle therefrom, means for

rotatably mounting said body portion on said car, an arm, means for pivotally connecting said arm to said body portion, said means adapted to raise and lower said arm when said shaft is rotated, said arm extending forwardly and laterally from said body portion and provided with an extension slidably engaging an eye in said pin, and means for rotating said shaft for elevating said pin.

5. In combination, a car, coupler mechanism for said car, including a coupler pin, a rock shaft provided with a normally downwardly extending handle at its outer end, and having a flattened intermediate portion 70 in a plane at right angles to said handle, an arm having one end bifurcated for engaging said flattened portion, and a pin extending downwardly through said flattened portion and the bifurcated end of said arm, said arm being provided with an off-set portion 75 for slidably engaging an eye in the upper end of said pin.

6. In an uncoupling mechanism for railway cars, a rock shaft comprising a substantially straight body portion and an operating handle secured to said body portion and extending at an angle therefrom, means for rotatably mounting said shaft on a car, an arm, a pivot extending parallel to said handle 90 and pivotally connecting said arm to said body portion and means rigidly connected to said arm for slidably engaging the eye of a coupler pin for operating the same.

7. In combination, a car, coupler mechanism therefor including a coupler pin provided with an eye, a substantially straight rock shaft comprising a substantially straight body portion, means for rotatably mounting said body portion on said car, an uncoupling arm, a normally vertically arranged pivot connecting said arm to the straight body portion of said shaft, said arm being provided with a reduced portion 100 for pivotally and slidably engaging said eye for permitting relative lateral and vertical movements between said arm and said pin, and a handle on said shaft normally extending downwardly for rotating said shaft to elevate said arm and pin.

8. In combination, a car, coupler mechanism therefor including a coupler pin having an eye therein, a rock shaft comprising a substantially straight body portion, bearings for said body portion, an arm having an interlocked pivotal connection with said shaft between said bearings, said connection being adapted to elevate or depress said arm when said shaft is rotated in one direction or the other, said arm being provided with means for rotatably and slidably engaging said eye, and a handle for rotating said shaft for lifting said pin.

9. A coupler pin lifter comprising a rock shaft member, and an arm member, one of 110

said members being provided with a recess and the other with a flattened portion for engaging said recess, and means for holding said flattened portion within said recess the 5 outer end of said arm being adapted to engage a coupler pin for lifting the same when said shaft is rotated.

10. A coupler pin lifter comprising a rock shaft having a flattened portion, and a lifting arm having a recess complementary to 10 and loosely fitting upon such flattened portion, and a pin for pivotally connecting said members together.

ARTHUR G. HAWKES.
